UNITED STATES PATENT OFFICE.

WILLIAM H. PACKER, OF COLUMBUS, OHIO.

STOP-DOOR-HINGE FIXTURE.

Application filed January 21, 1925. Serial No. 3,837.

This invention relates to stop door hinge fixtures, and has for its object the provision of a novel and improved spring actuated hinge fixture by means of which an associated stop door will be positively maintained in both its open and closed positions.

In the majority of spring actuated stove doors now in commercial use, it is customary to arrange the springs so that they will act upon the door to maintain the latter normally in a closed position. Whenever the door is opened or partially opened the tendency of the springs associated therewith is to force the door closed. This construction is objectionable in several respects, but one of the principal objections thereto is the necessity of applying force to keep the door open while the attendant is placing materials into or removing the same from the compartment of a stove closed by the door, since unless this pressure is applied to the door when open, the tendency of the same will be to swing about its pivot to a closed position with the likelihood of touching and burning the arms of the attendant. Because of this condition the present invention provides an improved and simplified type of spring hinge structure for stove doors which will automatically maintain itself in both open and closed positions and further, to construct the fixture so that the door may be opened and closed quickly and conveniently.

With these and other objects in view, as will appear as the description proceeds, the invention consists in the novel features of construction, combinations of elements and arrangements of parts hereinafter to be fully described and pointed out in the appended claims.

In the accompanying drawings:

Figure 1 is a front elevation of a stove provided with the spring hinge fixtures comprising the present invention.

Figure 2 is a rear elevation on a large scale of an oven door and disclosing the spring hinge fixtures associated therewith,

Figure 3 is a vertical longitudinal sectional view taken on the line 3—3 of Figure 2, and illustrating the position of the spring hinge fixture when the door occupies a closed position,

Figure 4 is a similar view illustrating the door when in its open position;

Figure 5 is a detail perspective view of the fixture removed from the stove, and

Figure 6 is a vertical sectional view showing a modified form of fixture.

Referring to the drawing the numeral 10 designates the oven casing of a stove or cooking range, although it will be apparent that in its scope the invention is not limited to oven or stove doors but may find use in connection with any type of swinging closure generally. For present purposes, however, the disclosure will be directed specifically to the use of the invention in connection with an ordinary form of domestic cooking range.

Constituting a part of the casing 10 is a channel door frame 11 which in this instance surrounds the opening 12 of an oven or other similar compartment 13 of the stove or range. A portion of the frame adjacent to the bottom of the compartment 13, is formed on the opposite sides thereof with slots 14, and the lower ends of these slots constitute fulcrum edges which are designated by the numeral 15. Arranged within the channel portions of the door frame 11 on opposite sides of the opening 12 is a pair of base plates 16. These plates are formed with slots 17 which register with the slots 14, and arranged to pass through the slots 14 and 17 is a pair of fulcrumed door supporting arms 18. The outer ends of the arms 18 terminate in brackets 19 which are secured as at 20 to cooperative brackets 21 provided in connection with the lower corners of an oven door 22. By this construction the door is supported by the brackets 19 and by being thus supported will fulcrum around the edges 15 when the door is being moved from open to closed positions.

The arms 18, as shown in Figure 3, extend downwardly and angularly and are provided with curved edges 23 which engage with the fulcrum edges 15 to pivotally support the door 22. The extreme lower ends of the arms 18 terminate in hook extensions, each of which includes a foot 24 and a curved rod receiving surface 25.

Cooperative with the surface 25 and adapted to ride thereupon is the lower bifurcated end 26 of a spring rod 27, one of which is provided in connection with each of the arms 18. These rods extend upwardly and have their upper ends slidably and loosely received within slots 28 provided in connection with out-turned spring seats 29 formed with the upper ends of the base plate 16. The rods 27 are formed with transverse pins 30, upon which seat the lower ends of expand-

sion coil springs 31, the upper ends of said springs being engaged with the seats 29.

In operation, it will be seen, by reference to Figure 3, that when the door is in a closed position, the arms 18 will extend downwardly with the rearwardly disposed cam surface 32 thereof in engagement with the lower ends of the rods 27. This construction and arrangement causes the rods to assume a position acutely angular to the vertical plane of the door frame 11, the closing of the door, and the consequent movement of the arms 18, causes the cam surfaces thereof 32 to wipe against the lower ends of said rods so that such ends will be forced upwardly to assume the angular position shown in Figure 3. When in this position the coil springs 31 are positioned so that the same may exercise their greatest effort upon the arms 18 by reason of the increased leverage obtained by the peculiar configuration of the arms 18. In other words the force exercised by the springs is applied to the outermost point of the arms 18 with respect to the fulcrum edges 15. Now, as the door is swung to assume the open position depicted in Figure 4 the foot extensions 24 provided on the extreme outer ends of the arms 18 then engage with the lower portions of the rods 27 and also, by reason of the engagement of the bifurcated ends 26 of the rods with the curved edges 25 of the arms 18, the said rods will be elevated placing the springs 31 under tension. The engagement between the foot extensions 24 of the arms 18 and the rods 27 results in rocking the rods inwardly, causing the same to ride upon the edges 25 until said rods assume a position wherein the weight of the door and due to the shifting of the rods near the fulcrum edges, the same will overcome the influence of the compressed springs 31 and thus maintain the door in an open position, thereby holding the door open until positive pressure is applied to swing the same to its closed position. In the modified form of the invention set forth in Figure 6 the same spring pressures are applied to the arms 18, but in lieu of the coil springs 31 I employ flat bow or leaf springs 33. It will be observed that the base plates 16 are maintained in their fixed positions by means of the arms 18, which pass through slots provided in said plates. This avoids the necessity of rigidly mounting the plates on the door frames, eliminates welding or fastening appliances, and furthermore enables the entire fixture to be assembled outside of the stove and then applied thereto in assembled form, and convenience and economy in the manufacture of the stove thereby resulting.

What is claimed is:

1. A spring hinge fixture for swinging closures comprising an arm projecting inwardly and rigidly from the swinging clo-

sure, a frame upon which the lower edge of said arm is fulcrumed, a cam edge formed upon the opposite edge of said arm with respect to the fulcrum edge, and spring means cooperative with the cam edge of said arm and neutralized in the open position and increasingly active as the door is moved to closed position.

2. A spring actuated hinge fixture for swinging doors comprising door extensions rigid with and projecting inwardly from the lower corners of a door, said extensions being formed to pass through openings provided in a cooperative door frame and to rest upon the lower portions of said openings for pivotal movement, the portions of said extensions lying within said door frame being formed to include opposed cam surfaces, and spring means cooperative with said extensions for applying spring pressure thereto between said cam surfaces, said cam surfaces operating to shift the operating positions of said spring means so as to neutralize the pressure thereof, whereby the door will be held in either its open or closed positions.

3. A hinge fixture for doors comprising angularly and inwardly directed projections or extensions projecting rigidly from the hinged edge of a door, said extensions being adapted to project through openings provided in a cooperative door frame, the extensions engaging with and being fulcrumed upon certain of the walls of said openings, said extensions within said frame being provided with a cam surface, spring means engaging with said cam surface and movable with respect thereto, and opposed operating projections provided upon said extensions at the terminating points of said cam surface and cooperative with said spring means when the door is operated to cause said spring means to assume positions with respect to said cam surface to neutralize the pressure thereof and maintain the door normally in either of its open or closed positions.

4. A hinge fixture for swinging doors comprising a bracket adapted to be secured to the hinged edge of a door, said bracket being formed to include an inwardly and angularly directed extension arranged to pass through and to be fulcrumed upon an opening provided in an associated door frame, one edge of said extension being formed with a cam surface, a spring pressure rod arranged for sliding engagement with said cam surface and projections provided upon said extension at the terminating portions of said cam surface and adapted for engagement with said rod so as to shift the latter with respect to said surface to occupy positions neutralizing the pressure thereof, thereby maintaining said door in either of its opened or closed positions.

5. In a stove, a door provided at its hinged edge with an inwardly extending arm, said arm being arranged to pass through a slot provided in the door frame, a cam surface 5 provided upon the portion of said arm lying within said frame, a base plate having a slot formed therein for the reception of said arm and arranged within said frame, a rod having the lower end thereof slidably engaged 10 with said cam surface and the upper end thereof provided loosely within an opening formed in the upper end of said plate, a coil spring disposed around said rod and contracted between said base plate and a fixed 15 projection formed on said rod, and projections provided upon said arm at the ends of said cam surface and cooperating with said rod to shift the latter automatically into engagement with different portions of said cam surface. 20
6. In a stove, a door provided with inwardly directed arms, said arms being fulcrumed within openings provided in the door frame, cam surfaces provided upon said arms within said frame, spring means 25 cooperative with said arms and slidably engaged with said cam surfaces, and means provided in connection with said arms for shifting automatically the positions of engagement between said spring means and said cam surfaces. 30

In testimony whereof I affix my signature.

WILLIAM H. PACKER.
